UNITED STATES PATENT OFFICE.

RALPH A. PICKETT, OF MADISON, KANSAS.

OIL-WELL-PUMP JACK.

Application filed June 25, 1927. Serial No. 201,454.

This invention relates to oil well pump jacks, and aims to provide a device of this character which is extremely simple in construction, and one that transmits a straight line movement to the pump rod.

In carrying out the invention I mount the structure on suitable supporting legs mounted for pivotal movement, with certain of said legs being adjustable to permit the jack to be shifted to an out of the way position when it is desired to pull the pump rod or tubing.

The nature and advantages of the invention will be better understood when the following detail description is read in connection with the accompanying drawings, the invention residing in the construction, combination and arrangement of parts as claimed.

20 In the drawings forming part of this application like numerals of reference indicate similar parts in the several views and wherein:

Figure 1 is a side elevation of the pump jack showing its normal position by full lines, and its adjusted position by dotted lines.

Figure 2 is a top plan view.

Figure 3 is a view taken at a right angle 30 to Figure 1.

Figure 4 is a sectional view on line 4—4 of Figure 3.

Figure 5 is a sectional view on line 5—5 of Figure 3.

35 Figure 6 is a fragmentary enlarged view of the cable connection between the drum and operating rod.

Figure 7 is a sectional view on line 7—7 of Figure 1.

40 Figure 8 is a view taken at a right angle to Figure 7.

Referring to the drawings in detail, 10 represents a substantially U-shaped frame, the sides of which are extended upwardly 45 at their forward end, and terminate to provide bearings 11 for the shaft 12 of a suitable drum 13. This drum is connected with the pump rod 14 by suitable means including a cable 15. This cable is bent upon itself as clearly illustrated, the looped end being clamped to the drum by a suitable block 16, while the parallel portions of this cable extend in the direction of the pump rod. Suitably coupled to the upper end of 55 this pump rod 14 is a rod 17 of substantially T-shaped formation, the head 18 of which

is provided with key-hole slots 19 which receive the adjacent parallel portions of the cable 15. The free ends of this cable are wedged or otherwise suitably secured to the 60 head 18 of this rod 17. Consequently when the drum is rotated in one direction, the cable 15 partly winds about the drum thereby lifting the pump rod 14, and when the drum rotates in an opposite direction, the 65 cable unwinds therefrom and lowers the pump rod.

While the drum may be rotated in any suitable manner, I preferably make use of a cable for this purpose which is formed substantially in the same manner as the cable 15 above described. The looped or intermediate portion of this last mentioned cable is passed around the block 21 which is secured to a clevis 22, the clevis in turn being 70 connected with a power rod 23. The parallel portions of this cable 24 extend in the direction of the drum 13, each parallel portion being received in a groove 25 formed in a band or ring 26 secured to the drum. 75 Carried by each band or ring is a hook 27 which is received by a loop 28 formed by the adjacent end of the cable 24. Manifestly the cable 24 is adapted to be wound about and unwound from the drum 13 in order to 80 rotate the latter in reverse directions, and thereby impart a straight line movement to the pump rod 14.

The drum 10 is mounted upon front and rear supporting legs all of which are pivotally mounted as at 29 upon suitable base pieces 30. The front pair of legs are indicated at 31, while the rear pair of legs include relatively adjustable sections 32 and 33 respectively. The section 32 of each leg 90 preferably slides within the section 33, while the sections are normally held fixed relatively by any suitable means indicated at 95 34. However, by reason of this construction the entire jack may be shifted from its normal position illustrated by full lines in Figure 1, to an out of the way position as shown by dotted lines in Figure 1 when it is desired to pull either the pump rod or tubing. Manifestly when the jack is shifted 100 to its adjusted position the rear legs telescope for this purpose.

While it is believed that from the foregoing description the nature and advantages of the invention will be readily apparent, I 110 desire to have it known that I do not limit myself to what is herein shown and de-

scribed, and that such changes may be resorted to when desired as fall within the scope of what is claimed.

What is claimed is:

- 5 1. A pump jack comprising a frame, supporting means therefor, a drum journaled on the frame, a cable folded upon itself and having its intermediate portion secured to said drum, and its parallel portions adapted 10 to be simultaneously wound about or unwound from the drum, a substantially T-shaped rod coupled to the adjacent end of the pump rod and having its head terminally slotted to receive the adjacent parallel 15 portions of the cable, whereby the latter are connected with the pump rod, and means for rotating said drum in reverse directions.
2. A pump jack comprising a frame, supporting means therefor, a drum journaled on the frame, a cable folded upon itself and attached to the drum and including parallel portions connected with the pump rod, said parallel portions of the cable being 25 adapted to be simultaneously wound about

or unwound from the drum, and means for rotating said drum in reverse directions, including a power transmitting rod, a second cable folded upon itself and having its intermediate portion connected with said rod, and parallel portions associated with said drum, spaced bands surrounding said drum and having grooves to receive the parallel portions of the second mentioned cable, and means carried by said bands for connecting the adjacent ends of the cables thereto. 30

3. A pump jack comprising a frame, a drum journaled thereon, means for rotating said drum, means connecting the drum with the pump rod to give the latter a straight 40 line movement, front and rear supporting legs for said casing, said legs being mounted for pivotal movement, and said rear legs including relatively adjustable sections whereby said frame may be shifted to an out of 45 the way position with relation to the pump as and for the purpose specified.

In testimony whereof I affix my signature.

RALPH A. PICKETT.
